Attorney

UNITED STATES PATENT OFFICE.

LU ELLA BUSBY, OF CALDWELL, KANSAS.

HEATER FOR POULTRY-HOUSES.

1,345,581.

Specification of Letters Patent.

Patented July 6, 1920.

Application filed September 23, 1919. Serial No. 325,811.

To all whom it may concern:

Be it known that I, LU ELLA BUSBY, a citizen of the United States, residing at Caldwell, in the county of Sumner and State 5 of Kansas, have invented certain new and useful Improvements in Heaters for Poultry-Houses, of which the following is a specification.

This invention relates to poultry houses, 10 and more particularly to heating means for such houses.

The object of the invention is to provide a simple and efficient heater constructed to uniformly heat a plurality of compartments, 15 the heating pipes being protected by suitable deflectors.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made 20 within the scope of what is claimed without departing from the spirit of the invention.

In the accompanying drawings:—

Figure 1 represents a longitudinal section through a house constructed in accordance 30 with this invention and equipped with this improved heater, parts being broken out, and

Fig. 2 is a horizontal section with parts of the pipe protector and deflector broken 35 out.

In the embodiment illustrated, a poultry house 1 is shown rectangular in form, although obviously it may be of any other desired configuration, and which is divided by 40 partitions 2 into a plurality of compartments, three of which are here shown, and numbered 3, 4 and 5. The central compartment 4, which is designed to contain a heating stove, and in which baby chicks are intended to be housed, has a door 6 to afford 45 access thereto while similar doors 3^a and 5^a afford access to the other compartments.

The stove 7 is shown mounted in the compartment 4 and the heat is generated therein 50 by means of a burner 8 supplied with fuel through a pipe 9, said fuel being gas, kerosene or any other suitable material of this character.

A tank 10 is disposed in a plane above the 55 heating stove 7 and has a pipe 11 leading from the bottom thereof which communica-

cates with a horizontally disposed branch pipe 12 having a cross pipe 13 at its outer end, said pipes 12 and 13 forming a T-shaped structure, the junction of the members of which extends into the stove 7 above the burner 8 and the arms 13 being arranged transversely across the compartment 4 as is shown clearly in Fig. 2. A pipe 14 is positioned around the side wall of the building 60 1 on its inner face passing through all of the compartments and is supported at a suitable distance above the floor by brackets 15, being preferably arranged about twelve or eighteen inches above the floor. Over this 65 pipe 14 is mounted a combined protector and deflector 16 which is arcuate in cross section being secured at one edge to the side walls of the building and curves downward over the pipe or conduit 14, and directs the 70 heat from the pipe toward the floor on which the chicks will huddle. It is of course to be understood that the compartments 3 and 5 are designed to contain chicks of different sizes, the babies being placed in the central 75 compartment where the heat is most intense.

The tank 10 is preferably provided with a steam escape 17 so that should the water in the pipes become excessively hot, the steam generated will pass out through said 80 escape 17 without danger of injuring the apparatus.

It is of course to be understood that the size of the house and the compartments may vary and that the burner and water heating 85 pipes may also be of various sizes to suit the size of the building to be heated.

With a house constructed and heated as above described, no hovers such as are usually employed in brooders are necessary, 95 since the deflector 16 will direct the heat downwardly to the floor and keep the chicks comfortable without further protection.

From the foregoing description, taken in connection with the accompanying drawings, the advantages of the construction and of the method of operation will be readily apparent to those skilled in the art to which the invention appertains and while I have described the principle of operation of the 100 invention together with the device which I now consider to be the best embodiment thereof, I desire to have it understood that the device shown is merely illustrative and that such changes may be made as are 105 within the scope of the claimed invention.

Having thus fully described my invention,

what I claim as new and desire to secure by Letters Patent, is:—

1. The combination with a compartment having a heater therein; of a water conduit arranged around the inner wall of said compartment, a tank supported above said heater, a T-shaped pipe having the intersection portions thereof positioned over the heater, the stem of said pipe communicating 10 with the tank and its arms arranged transversely of the compartment and communicating with said conduit on opposite sides of the compartment.
2. The combination with a compartment 15 having a heater therein; of a water conduit

arranged around the inner wall of said compartment, brackets supporting said conduit, means for heating the water therein, and a combined protector and heat deflector secured to the compartment wall above said conduit, said deflector being arcuate in cross sections and curving down over the conduit to direct the heat from the conduit downward onto the chicks.

In testimony whereof I affix my signature 25 in presence of two witnesses.

MRS. LU ELLA BUSBY.
